UNITED STATES PATENT OFFICE.

ERNEST CULLEN AND GUSTAF SJOLANDER, OF MIDLAND, MICHIGAN, AS-SIGNORS OF ONE-THIRD TO JAMES H. JOHNSON, OF MIDLAND, MICHIGAN.

SHOE-LACE HOLDER.

No. 857,448.

Specification of Letters Patent.

Patented June 18, 1907.

Application filed June 9, 1906. Serial No. 321,023.

To all whom it may concern:

Be it known that we, ERNEST CULLEN and GUSTAF SJOLANDER, citizens of the United States, residing at Midland, in the county of Midland and State of Michigan, have invented new and useful Improvements in Shoestring-Holders, of which the following is a specification.

This invention relates to shoe lace holders of the type employed on shoes for clamping the loose ends of the lacing strings, and has for its objects to provide a comparatively simple, inexpensive device of this character which may be conveniently applied for use, one whereby the free ends of the strings will be securely clamped to prevent the string from becoming untied, and one with which the string may be conveniently engaged or disengaged.

With these and other objects in view, the invention comprises the novel features of construction and combination of parts more fully hereinafter described.

In the accompanying drawings: Figure 1 is an elevation of a portion of a shoe upper equipped with holders embodying the invention. Fig. 2 is a rear face view of one of the holders. Fig. 3 is a central, longitudinal section through the same, taken on the line 3—3 of Fig. 2. Fig. 4 is a detail cross section taken on the line 4—4 of Fig. 2.

Referring to the drawings, 1, 1, designate the lacing flaps of a shoe provided with lacing hooks 2 adapted for engagement by a lacing string 3 tied in a bow 4 as usual above the uppermost hooks 2 and having its end portions 5 engaged with holders 6 attached to the flaps 1 above the respective rows of hooks 2. These parts, with the exception of the holders 6, may all be of the usual or any appropriate construction and material and are adapted in practice to perform their ordinary functions.

The holders 6, which are identical in construction and operation, are each constructed from a single piece or blank of sheet metal, which, after being formed, is bent into shape to provide a front clamping member or jaw 7 having a central, longitudinal opening or slot 8 and a rear clamping member or jaw 9 having a central, longitudinal web or tongue 10 of substantially semicircular form in cross section adapted to lie within the opening 8, the upper end of the jaw

being rearwardly bent or overturned as at 11 55 to provide between the upper ends of the jaws an entrance space or opening 12 through the medium of which the string may be readily introduced into the holder. Provided on the jaw 9 at opposite sides of the 60 web 10 are side portions or strips 13 which extend diagonally from a point adjacent the lower end of the web 10 to the overturned end of the latter for bracing and strengthening the upper portion of the jaw, the overturned portion 11 of which terminates in a sharpened engaging spur 14, while formed on the holder 6 at its lower end and at opposite sides of the jaw 7 is a pair of sharpened engaged portions or spurs 15 which serve in 70 conjunction with the spur 14 for attaching the holder to the shoe flap.

In practice, after lacing the shoe the string is tied to form the bow 4 and the end portions 5 are engaged respectively with the 75 holders, as before explained. In engaging the string with the holders the end portions 5 are extended across the entrance spaces 12 and drawn downward between the jaws, it being noted that when drawn downward between the jaws the said portions of the string will lie transversely of and be pressed into the slots 8 under the action of the webs 10 and be securely held between the latter and the side walls of the slots. It is apparent 85 that, if desired, the loops of the bow may, either alone, or together with the companion end portions 5, be engaged with the holders for securing the lace, and further, that if the length of the string is such as to preclude tying into a bow, the ends of the strings may be secured by engagement with the holders, thus to prevent accidental unlacing of the shoe. It will be observed that under this construction the end portions of the string 90 will be securely held to prevent the bow from becoming untied and that the string may be conveniently engaged with or disengaged from the holder.

Having thus fully described my invention, what I claim is:

A shoe lace holder composed of a single piece of sheet metal folded to form co-operating front and rear spring clamping jaws, the front jaw being provided with a longitudinal opening and terminated at its lower end in a pair of rearwardly projecting engaging spurs, the rear jaw being flared at its upper end to

form an entrance space between the upper ends of the jaws, a transversely curved, longitudinal web struck from the rear jaw to seat in said opening, bracing strips formed at the sides of said web and terminally joined to the rear jaw for strengthening the same, said strips being extended from the upper flared end of the jaw to a point adjacent the lower end thereof, and a sharpened engaging spur formed on the upper end of

the rear jaw and adapted for coöperation with the first named spurs for attaching the holder to the shoe.

In testimony whereof, we affix our signatures in presence of two witnesses.

ERNEST CULLEN.
GUSTAF SJOLANDER.
